UNITED STATES PATENT OFFICE.

EDWARD L. HALL, OF BROOKLYN, NEW YORK.

DESIGN FOR A GAME-BOARD.

SPECIFICATION forming part of Design No. 25,252, dated March 17, 1896.

Application filed January 18, 1896. Serial No. 576,044. Term of patent 3½ years.

To all whom it may concern:

Be it known that I, EDWARD L. HALL, a citizen of the United States, residing at Brooklyn, in the county of Kings, State of New York, have invented and produced a new and original Design for Game-Boards, of which the following is a specification, reference being had therein to the accompanying drawings.

Figure 1 is a plan view of my game-board, 10 and Fig. 2 is a perspective view thereof.

Like letters of reference indicate like parts in both of the views.

The leading feature of my design consists in the raised circular centrally-disposed band 15 with openings therein, with a pictorial representation within the space inclosed by said band.

A is the surrounding wall of the box, and B the angular partitions at the corners thereof, with spaces for openings *b* between one end 20 of each partition and the adjacent wall of the box.

C is the circular band, D its openings, and E the pictorial representation.

What is claimed as new is—

The design for a game-board substantially 25 as herein shown and described.

In testimony whereof I affix my signature in presence of two witnesses.

EDWARD L. HALL.

Witnesses:

WILLIAM H. MELTEER,
OTTO E. FIGGE.
